UNITED STATES PATENT OFFICE.

MATTHEW WOESSNER, OF BROOKLYN, NEW YORK, AND HENRY BIRNN, OF JERSEY CITY, NEW JERSEY.

BEVEL-SQUARE.

SPECIFICATION forming part of Letters Patent No. 245,596, dated August 9, 1881.

Application filed May 27, 1881. (No model.)

To all whom it may concern:

Be it known that we, MATTHEW WOESSNER, a resident of Brooklyn, county of Kings, and State of New York, and HENRY BIRNN, a resident of Jersey City, county of Hudson, and State of New Jersey, have invented certain new and useful Improvements in Bevel-Squares; and we do hereby declare that the following is a full, clear, and exact description thereof, reference being had to the accompanying drawings, and to the letters of reference marked thereon, making a part of this specification.

This invention relates to an improvement in try-squares, whereby the same instrument may serve equally well as a try-square and as a bevel-square, capable of accurate adjustment to any desired angle.

It consists in so fitting a rectangular arm within a rectangular recess cut in the side of the tool-stock as that the arm shall completely fill out the recess and present a flush, even surface and form a perfect straight edge for the tool on either side as well as at its ends; also, in pivoting and securing the inner end of said arm to the stock by means of a semicircular offset or plate at said inner end fitting into a corresponding slot or mortise cut in the stock, the offset being provided with one or more semicircular projections fitting within counterpart grooves in the slot.

The face of the semicircular plate is marked off with a scale of degrees, which, being visible through a small opening cut in the face of the stock, serves to indicate the angle which the arm forms with the stock, from one degree to ninety degrees.

In the accompanying drawings, Figure 1 is a plan view of our improved bevel-square with its pivoted arm swung open to form a right-angle square. Fig. 2 is a longitudinal section in line *x x*, and Fig. 3 a transverse section in line *y y*, of Fig. 1; and Fig. 4 is a plan view of the blade or arm detached.

A is the stock or body of the square, having a longitudinal rectangular recess, *D*, cut away on one side thereof, parallel to the side of the stock, and at a right angle to its end. The outer side of the stock and the inner side of the recess *D* are marked off with a scale for ordinary use.

B is an arm of the same thickness as the

stock *A*, and of dimensions to exactly fill the recess *D*, so that when laid or closed therein its outer edge and end will come flush and form a perfectly straight edge with the side and end of the stock. (See dotted line, Fig. 1.)

The inner end of the arm *B* is provided with an offset, *C*, a portion of which projects at right angles, and whose outer edge, forming the end of the arm, is furnished with a semicircular curve, as shown in Fig. 4. The thickness of this offset is less than that of the stock *A*, and a slot is cut centrally through in the thickness of the stock *A*, at the inner angle of the recess *D*, conforming in dimensions and shape with the offset *C*, to receive the same. One or more semicircular ridges, *a a*, Figs. 2, 3, and 4, are formed upon the face of the offset *C* of the arm, and counterpart grooves are formed in the slot in the stock *A*, so that when the one is fitted into the other a hinged joint is thereby formed, which permits the arm to turn in the slot, but prevents its withdrawal therefrom.

To permit the introduction of the end of the arm into the slot the stock *A* is formed in two divisions, *S S*, (see Fig. 2,) which are riveted together after the arm has been placed in position.

The ridge *a* in the offset *C* of the arm is laid off and marked with a scale of degrees, (see Fig. 4,) and an aperture, *c*, is cut in the face of the stock, through which the graduated arc is visible, whereby the angle of the arm *B* with the stock is constantly indicated to the eye. The continuity of the inner edge of the arm *B*, in full width, is maintained to its intersection with the inner edge of the stock *A* by means of a shoulder, *f*, formed upon both sides thereof along the edge of the offset *C* to its inner angle. (See Figs. 1 and 4.)

The instrument thus constructed presents no outer curved or irregular edges when opened or closed; but its edges are true and straight in all positions, and it is equally well adapted for a straight-edge rule or a try or bevel square. The arm facilitates the laying out or measuring of any angle up to ninety degrees, the angle being readily read off upon the graduated arc.

Instead of securing the joint between the arm and stock by means of a ridge or projection upon the offset *C* fitting into counterpart

grooves in the slot in the stock, which necessitates a division of the stock to permit of the introduction of the offset into the slot, the offset may be adapted to slip into the slot and 5 be secured by means of a transverse pin passing through a curved slot in the offset.

What we claim as new, and desire to secure by Letters Patent, is—

- 10 1. A stock, A, having a rectangular recess upon one side thereof, and provided with an arm, B, pivoted to the stock by means of an offset fitting and working in a semicircular slot cut in the stock at right angles to said recess, substantially as and for the purpose herein set 15 forth.

2. The two plates in the divided stock A, provided with semicircular grooves in a recess formed between its divisions, in combination with an offset, C, upon the inner end of an arm, B, provided with projections *a a*, to fit into said 20 grooves and form a hinged joint, substantially as and for the purpose herein set forth.

In testimony whereof we have signed our names to this specification in the presence of two subscribing witnesses.

MATTHEW WOESSNER.
HENRY BIRNN.
